APPARATUS FOR DETERMINING ALIGNMENT OF LOCOMOTIVE SMOKESTACK AND EXHAUST PIPE

John Uhrin, Philadelphia, Pa.

Application June 28, 1938, Serial No. 216,315

2 Claims. (Cl. 33—180)

This invention relates generally to an improved apparatus and method for determining the exact alignment of a locomotive smokestack with an exhaust pipe.

5 The usual practice of locomotive builders in aligning the smokestack and exhaust pipe has been to support the boiler in a level position and employ a plumbob for determining the necessary vertical alignment between the smokestack 10 and pipe. This procedure required the use of a crane to assist in levelling the boiler as well as requiring the services of several men.

It is an object of my invention to provide an 15 improved method and apparatus whereby a smokestack and exhaust pipe may be effectively brought into alignment with each other regardless of the position or location of the boiler.

Other objects and advantages will be more apparent to those skilled in the art from the following description of the accompanying drawing in 20 which:

Fig. 1 is a transverse section through a smokestack and exhaust pipe with the boiler partially shown;

25 Fig. 2 is a plan view taken on the line 2—2 of Fig. 1.

In the particular embodiment of the invention, such as is disclosed herein merely for the purpose of illustrating one specific form among possible others that the invention might take in 30 practice, I have diagrammatically shown the invention as applied to a boiler 1 having a smokestack 2 with its usual component parts 3 and 4. A conventional exhaust pipe 5 connected to the 35 engine cylinders is supported upon the upper end of a usual exhaust passage structure 6 extending upwardly into a customary cylinder saddle not shown.

It is of the utmost importance that the exhaust 40 pipe 5 and smokestack 2 be in axial alignment with each other, and to that end I have provided a template 8 of any suitable shape but having particularly a centering tongue or projection 9 of the same diameter as the upper end of exhaust 45 pipe 5. Two supporting ledges 10 lie in the same plane with each other and normally rest on the upper end of exhaust pipe 5 while a line, scribed or formed by any suitable indentations in the form of center punch marks 11, extend in a plane 50 at right angles to the plane of shoulders 10. A small hole 12 is formed to the lower portion of template 8 and an indicating element such as a string or a fine linen thread 13 is secured to said hole 12 and extends upwardly to be tied to, or extend through an opening in, a rod or piece of wood 14 which rests upon the upper end of smokestack 2.

In operation, the rod 14 is suitably positioned on the upper end of smokestack 2 so that string 13 lies in the center of the stack. This can be readily accomplished merely by measuring the distance of the string from two sides of the smokestack at 90° apart. The operator next places and manually holds the template 8 firmly on top of exhaust pipe 5 in the position as shown and observes whether the tautly drawn string 13 falls in alignment with the line formed by the series of center punch marks 11. The operator then rotates the template 8 through 90° and again observes whether the string 13 is in alignment with the line. If such alignment is obtained through the two vertical planes at 90° to each other, then the stack and exhaust pipe are in alignment with each other. If the string and line 11 are not in alignment with each other, the stack 5 can be shifted either sidewise or forwardly or backwardly depending upon the direction that 20 is necessary to bring the string and line in alignment.

As a result of my foregoing improved method and apparatus, it is seen that the exhaust pipe and smokestack can be readily aligned with minimum effort and time and regardless of whether the boiler is level or lying on its side or in any other irregular position.

It will of course be understood that various changes in details of construction and arrangement of parts may be made by those skilled in the art without departing from the spirit of the invention as set forth in the appended claims.

I claim:

1. Apparatus for determining the alignment 35 of a locomotive exhaust pipe and smokestack comprising, in combination, a template having means for supporting and centering the same upon the upper end of an exhaust pipe, a line located on said template so as to be coaxial of 40 said exhaust pipe when placed thereon, an indicating element secured to the lower portion of said template at a point which is in alignment with said line, and means for supporting the upper end of said element in the center of the 45 smokestack, whereby when said exhaust pipe and smokestack are in alignment with each other said indicating element is in alignment with the entire length of the line on said template.

2. The combination set forth in claim 1 further 50 characterized in that said template comprises a flat sheet metal member having supporting shoulders and a center tongue adapted to project into the exhaust pipe.

JOHN UHRIN.
